UNITED STATES PATENT OFFICE.

ARTHUR FREDERICK EVANS, OF CAMBRIDGE, ENGLAND.

INTERNAL-COMBUSTION ENGINE.

SPECIFICATION forming part of Letters Patent No. 732,343, dated June 30, 1903.

Application filed February 24, 1903. Serial No. 144,768. (No model.)

To all whom it may concern:

Be it known that I, ARTHUR FREDERICK EVANS, engineer, a subject of the King of Great Britain, residing at 11 Brunswick 5 Walk, Cambridge, England, have invented certain new and useful Improvements in Internal-Combustion Engines, of which the following is a specification.

The object of this invention is to construct 10 a noiseless engine in which the valves do not jam and the hydrocarbon-supply is not affected by cold and in which there is no possibility of hydrocarbon entering the crank-chamber and causing "crank-chamber fire."

15 The drawings illustrate an engine made in accordance with this invention.

Figure 1 is a vertical section. Fig. 2 is a transverse section on the line 2 2, Fig. 1; and Fig. 3 is a transverse section on the line 3 3, 20 Fig. 1.

The cylinder *a* is provided with a crank-chamber *b* and inlet and exhaust ports *c* and *d*, respectively, the ports being closed by the piston *e* and the inlet-port *c* being in free 25 communication with the crank-chamber. A pipe *f*, preferably terminating in a taper bore or nozzle, projects into the inlet-port *c* and leads to the bottom of a fuel-receiving chamber *g*, preferably adjacent to the inlet-port, 30 and cast in one piece with the cylinder. This chamber is in constant communication with the crank-chamber. Preferably the bottom of the chamber *g* is concave and is just below the level of the inlet-port.

35 Leading into the chamber *g* is a duct *h*, communicating with the fuel-supply. In this duct is a screw-plug *i* and a ball-valve *j* for regulating the flow of hydrocarbon and also acting as a non-return valve, which closes 40 when there is any pressure in the chamber *g*.

In the crank-chamber *b* is a valve *k* for the admission of air, which consists of a perforated plate *l*, with a disk *m*, of india-rubber, secured to the plate at the center.

45 The ignition may be on any system, but I prefer the timed low-tension spark.

The cylinder-head *n* is shown as being concave on the inside, and it is surrounded by a hood *o*.

50 The operation of the engine is as follows: On the upstroke of the piston (I refer to a vertical engine) a partial vacuum is formed

in the crank-chamber *b* and air enters it. The vacuum is communicated to the hydrocarbon-chamber *g*. Consequently the ball-valve *j* is lifted and a certain quantity of hydrocarbon is drawn into the chamber, the quantity being regulated by means of the plug *i*. On the end of the upstroke the disk *m* in the crank-chamber closes the perforations in the plate *l*, and on the descent of the piston the air is compressed, so that at the end of the stroke the air in the crank-chamber and the air in the hydrocarbon-chamber *g* is under compression and the proper charge 65 is collected at the bottom of the chamber *g*. First the exhaust-port *d* and then the inlet-port *c* are opened at the end of the stroke and the air in the crank-chamber expands into the cylinder *a*, first scavenging the remainder of the previously-burned charge and then carrying with it the new charge, which has been carried up by the air expanding out of the chamber *g*, spraying it at the entrance of the port. The charge is deflected upward 70 in the usual manner by a projection *p* on the piston *e*, vaporizing as it goes, and is then compressed in the cylinder and fired.

The engine is preferably regulated by a valve in the crank-chamber, which can be 80 opened and closed at will. This valve may conveniently consist of openings *q* in the wall of the chamber *b*, and a plate *r*, pivoted at *s* above them. A handle *t* is provided at the side for turning the plate *r*. By more or less 85 destroying the partial vacuum and compression in the chambers *b* and *g* the amount of air and hydrocarbon that enters the cylinder is regulated.

What I claim is—

1. In an internal-combustion engine, the combination of a working cylinder provided with admission and exhaust ports, a piston working in said cylinder, an air-compressing chamber intermittently put into communication with the working cylinder as the piston reciprocates, a fuel-receiving chamber in constant communication with the air-chamber and intermittently connected with the working chamber as the piston reciprocates, and 95 a fuel-supply passage leading to the fuel-receiving chamber, the organization being such that as the piston reciprocates fuel is sucked into the fuel-receiving chamber, then air is 100

compressed therein, and then the fuel and air pass from the fuel-chamber with air from the compressed-air chamber to the cylinder.

2. In an internal-combustion engine, the combination of a working cylinder, a crank-chamber, a piston reciprocating in the cylinder, a passage leading from the crank-chamber to the cylinder, an inlet-port at the end of the passage adapted to be opened and closed by the piston, a fuel-receiving chamber communicating with the crank-chamber, a pipe terminating at the inlet-port and leading into the fuel-receiving chamber and permanently communicating with the crank-chamber, an outlet-port adapted to be opened and closed by the piston, and a fuel-supply passage leading to the fuel-receiving chamber.

3. In an internal-combustion engine, the combination of a working cylinder, a crank-chamber, a piston reciprocating in the cylinder, a passage leading from the crank-chamber to the cylinder, an inlet-port at the end of the passage adapted to be opened and closed by the piston, a fuel-receiving chamber communicating with the crank-chamber, a pipe terminating at the inlet-port and leading to near the bottom of the fuel-chamber,

an outlet-port adapted to be opened and closed by the piston, and a fuel-supply passage leading to the fuel-receiving chamber. 30

4. In an internal-combustion engine, the combination of a working cylinder provided with admission and exhaust ports, a piston working in said cylinder, a crank-chamber intermittently put into communication with the cylinder as the piston reciprocates, an automatic inwardly-opening valve for admitting air to the crank-chamber, a regulating-valve in the crank-chamber, a fuel-receiving chamber in constant communication with the crank-chamber and intermittently connected with the working cylinder as the piston reciprocates, and a fuel-supply passage leading to the fuel-receiving chamber, the organization being such that as the piston reciprocates 45 fuel is sucked into the fuel-receiving chamber, then air is compressed therein, and then the fuel and air pass from the fuel-chamber with air from the compressed-air chamber to the cylinder.

ARTHUR FREDERICK EVANS.
